tion of New York

Filed Feb. 23, 1965, Ser. No. 83,944

Term of patent 14 years

(Cl. D34—15)

FIG. 1

FIG. 2

FIG. 3

FIG. 4

FIG. 5

FIG. 1 is a perspective view of an action toy showing my new design;

FIG. 2 is a front elevation thereof;

FIG. 3 is a rear elevation thereof;

FIG. 4 is a side elevation thereof, and

FIG. 5 is a top plan view.

The dominant features of my design reside in the portions shown in full lines.

The broken lines indicating a pull strap have been omitted from FIGS. 2-5 for convenience of illustration.

I claim:

The ornamental design for an action toy, substantially as shown and described.
